UNITED STATES PATENT OFFICE

2,245,942

APPARATUS FOR SEPARATING MATERIAL

Earl Stump, Harvey, Ill., assignor to Roberts and Schaefer Company, Chicago, Ill., a corporation of Illinois

Application June 29, 1934, Serial No. 733,053
Renewed October 20, 1938

27 Claims. (Cl. 209—475)

My invention relates to apparatus for gravitationally separating particles of different specific gravities and while especially applicable to and useful in connection with the cleaning of coal by air, it may be used equally well for separating other material both by the use of air, gas, or other fluid separating or floating media.

One object of my invention is to provide a machine which can be applied to the separation of fragmentary material in one operation through a comparatively wide range of sizes, thereby dispensing with excessive preliminary screening.

Another object of my invention is to provide an air separating device wherein with slight changes, the device may be used for many different size ranges so that the problem of maintaining a stock of machines is minimized.

Another object is to provide an air separating apparatus wherein the major part of the apparatus is the same for all sizes and conditions and only a relatively small part of the apparatus needs to be changed to take care of varying operating conditions.

Another object is to provide a material separating device which will be simple, light, inexpensive and large capacity, take up a minimum amount of room, have a minimum of vibration and require a minimum of power.

Other objects will appear from time to time throughout the specification and claims.

My invention is illustrated more or less diagrammatically in the accompanying drawings, wherein—

Figure 1 is a side elevation of the device;

Figure 2 is a longitudinal section on an enlarged scale through the device shown in Figure 1;

Figure 3 is a section along the line 3—3 of Figure 1;

Figure 4 is an enlarged section along the line 4—4 of Figure 2;

Figure 5 is an enlarged section along the line 5—5 of Figure 4;

Figure 6 is a section somewhat similar to Figure 2 and intended especially for the purpose of showing the way in which the interchangeable resistance bed and air chamber is assembled with the machine;

Figure 7 is a detail longitudinal section along 50 a line similar to the section in Figure 2 showing a modified form of the device;

Figure 8 is a section along the line 8—8 of Figure 7;

Figure 9 is a section along a line similar to the 55

section in Figure 7 but showing a further modified form;

Figure 10 is a section along the line 10—10 of Figure 1;

5 Figure 11 is a section through a modified form of resistance bed and air box.

Like parts are indicated by like characters throughout the specification and drawings.

It will be understood in general that my apparatus 10 comprises a hopper or chute through which coal or other material to be classified is fed, a gate associated with a reciprocating feeder for controlling the flow of the raw material to the machine, a source of air, gas or fluid under pressure and means for controlling the rate at which the fluid is supplied, a valve which independent of the general rate of flow causes the fluid to move with a pulsating stream, an air chamber adapted to receive this fluid and a previous resistance bed bounding the upper side of the air chamber so that a pulsating current of air, gas, or liquid is discharged upwardly through this resistance bed, the feeder meanwhile supplying a stream of fragmentary or comminuted material which is caused to flow downwardly across the top of the resistance bed. The pulsating air current floats the material, exerting a more pronounced effect on the light material than on the heavy so as to cause generally horizontal stratification, the stream of material being more or less homogeneous at its upper end and gradually becoming stratified at its lower end so that at the lower end a horizontal separation may be made into preferably three classes,

20 heavy at the bottom, middlings at the center and light at the top. The floating and separating effect of the air current is assisted by means of stirring or supporting means immersed in the air stream, which tends to assist the air stratification in part at least by supporting the weight of the current or stream of material.

25 The control is generally pneumatic responsive to variation in the pressure in the air box and preferably affects the rate at which the heavy material and the middlings are discharged from the apparatus. The pneumatic apparatus is manually adjusted to provide the desired operation.

The apparatus described and shown is applicable for treating any type of material and for any size range, changes to take care of variations being made by changing the air box and the resistance bed and by changing the angle of inclination of the resistance bed along which

the material flows and by the other adjustments as shown.

The reference numerals 1 and 2 indicate horizontal main supporting channel frame members. Projecting upwardly from them are vertical columns 3, 4, 5. These columns support an end plate 6, and side plates 7 and 8. Above these, are transparent side plates 9, 10, these plates being bounded along their upper edges by beams 11, 12, which beams carry a closed air and dust receiving hood 13. The columns 5 have associated with them an end plate 14 and side plates 15 to form a control and chute containing structure which may be separately removed from the apparatus without interfering with the panels 7, 8, 9, 10. Projecting upwardly from the members 1, 2 are columns 16, which together with the columns 3 carry a platform 17, which platform supports an eccentric shaft 18 driving by means of a link 19 a cross member 20 which in turn drives a reciprocating feeder plate 21 adapted to travel on rollers 22. This feeder plate forms the bottom of a feed box 23 having an adjustable gate 24 adapted to receive material to be treated from the bottom of a hopper 25.

The numeral 26 indicates a blower mounted on the beams 1 adapted to discharge air or gas under pressure through the pipe 27, the discharge of air being controlled by the butterfly valve 28 having an adjusting handle 29 and a lock screw 30 traveling along a quadrant 31. The pipe 27 communicates with the pipe 32 mounted on the columns 16 and 33. The numeral 34 indicates a butterfly valve contained within the pipe section 32 driven by a belt 35 on a pulley 36 from any suitable source of power not here shown. A sprocket 37 associated with the belt pulley drives a chain 38 which by means of a sprocket 39 drives the eccentric shaft 18. The rotation of the butterfly valve alternately opens and closes the pipe 32 so as to provide for a pulsating flow of air or gas from the blower to the apparatus.

The numeral 40 indicates an air box. It has downwardly extending flanges 41 adapted to travel on rollers 42 supported on the side frames 7. This air box is closed at bottom, sides and front. At the rear end it terminates in a sleeve 43 communicating by means of a flexible conduit 44 with the pipe 32 so that the pulsating stream of air is fed to the interior of the air box.

The air box is bounded on its upper side by a marble pack 45. This marble pack is contained between an upper perforate plate 46 rigidly mounted on the air box and a lower adjustable plate 47 which may be moved toward and from the upper plate by means of a series of adjusting screws 48. These screws may be manipulated to control the density of the pack, to control the angle of the plates 46 and 47 as the case may be and to exert a sufficient pressure on the marbles which marbles may be ceramic or metallic or even of other material as the case may be. It will be understood that this marble pack exerts a fixed but controllable resistance to the escape of air through the air box through the perforate wall 46. All the air fed to the air box by the blower through the fixed butterfly valve and through the pulsator is compelled to escape through the marble pack upwardly through the treatment zone.

In the device shown in Figures 1, 2, the slope of the air box and the marble pack is controlled by means of the adjusting screw 49 pivoted at one end on a bracket 50 associated with the rear-

most end of the air box, extending up through a bracket 51 on the end wall 6 and associated with an adjusting nut 52 whereby the air box may be raised and lowered rotating about the pivot pin 53, its lower position being limited by its engagement with the rollers 42.

In the modified form shown in Figure 6, the means for adjusting the air box is somewhat different. There we have a winch 54 on a bracket 55 on the column 16. A cable 56 is wound about that winch and engages a clevice 57 on the bracket 50. As shown in Figure 6 in full lines, the air box is being drawn into position by means of the winch, the pivot pin 53 having not yet engaged the slot 58 in which it will seat when the air box is in position. When the air box has been drawn to the position shown in dotted lines, 53 will seat in 58, then the cable will be released and brought up over the pulley 59. After that the angular adjustment of the air box can be made by exerting a tension on the cable through the windlass, the air box for instance being raised to the position shown in dot and dash lines in Figure 6. In either case, the air box may be additionally locked in position by means of the hand screws 60 traveling in slots 61 in the plates 7 which screws also tend to clamp the plates against the air box and prevent leakage of air outwardly and downwardly along the walls of the air box from the working chamber above the box.

The working chamber wherein the separating is done is of course the chamber between the glass or transparent panels 9, 10, the perforate plate 46 and the hood 13. The feeder 21 discharges the material to be treated into that chamber, the material falling upon the perforate plate 46 until a bed of flowing material such as is shown in Figure 2 has been formed.

The bed of material is relatively deep. The material as it feeds in is as shown in Figure 2 generally homogeneous. The pulsating effect of the air tends to float the material downwardly along its inclined path, much as it would be floated in a stream of water. The vibration of the bed itself, there being no vibration of the machine, tends to assist a gradual stratification as is indicated more or less in the drawing, the heavier materials tending to seek the bottom of the bed, the lighter particles tending to seek the top and there being an intermediate or middling zone. In order to assist in this action, stirring means are provided.

The stirring means may take a number of different forms. For instance, in Figures 2 and 3, we have two longitudinal bars 62 having a plurality of cross bars 63 forming a kind of a grid iron, there being lugs 64 projecting from this grid iron, the lugs being suspended from hanger bars 65 on the cross bars 66. A link 67 extending forwardly from one of the lugs 64 to a rock arm 68 reciprocates the grid iron. The rock arm 68, having a series of adjusting holes 69 at one end to any one of which the link 67 may be pivoted, is driven at its other end by means of a connecting rod 70, which is associated with the reciprocating feeder 21 so that the movement of the grid iron is in consonance with the reciprocation of the feeder and so also with the movement of the pulsator valve. The movement of the grid iron may, however, be independent of the feeder and valve.

In the modified form shown in Figure 7, instead of using a grid iron, a plurality of parallel perforate plates 71, 72 are used, the plates 71, 72 being spaced and held together by means of

adjusting bolts 73 and suspended from hanger rods 74. In this case a connecting rod 75 extends between the reciprocating feeder 21 and a lug 760 on the upper one of the plates 71. It will be noted from Figures 7 and 8, that in this case the slots in the plates are longer in a longitudinal direction than their width and these plates similar to the grid iron are so disposed that at least the lowermost one is rather close to the perforate material supporting surface which bounds the upper side of the marble pack.

The operation of these plates or of the grid iron is two-fold. It tends to guide the flow of material along lines parallel with the supporting surface on the upper wall of the marble pack and to support part of the weight of the material so as to prevent an undue increase in density of the flowing material from top to bottom. Also it tends to stir the material and assist by imparting longitudinal vibration to the flowing particles in the stratification effect imparted by the transverse vibration from the air stream. An additional important effect of the grid or plate is that by its movement, it tends to break down and interrupt incipient blowing through the bed by closing up air pipes or pockets which may be formed in the material. The movement of the zoning plate is slow and perhaps should be described as longitudinal displacement rather than longitudinal vibration and its stirring and supporting function in connection with stratification loosen the bed to permit stratification and in connection with the preventing of air blasts through the bed is of the utmost importance.

In the modified form shown in Figure 9, the plates 76, 77 are mounted on the rods 78 but are held quiescent in the bed of material having no stirring effect though the stratifying, guiding and load supporting effect is the same.

Projecting downwardly from the floor of the air box 40 is a sleeve 79. A flexible conduit 80 joins the sleeve with a pipe 81 mounted in the main supporting frame. This pipe is adapted to be controlled by means of a butterfly valve 82 with controlling handle 83. The pipe extends outwardly through the frame and has an upward extension 84 surrounded by a water box 85. This water box 85 is closed by a cover 86. It contains water 87, and has immersed therein a float cylinder 88 open at the bottom and enclosing the tank 84, there being an air chamber 89 formed between the water and the floating member 88. Projecting upwardly from the float cylinder 88 is a control rod 90 passing out through the cover 86 by way of a packing gland 91. This rod 90 terminates in a yoke 92 pivoted on the operating lever 93, which lever in turn is pivoted on a hanger 94 on the main frame. It will be understood that the pressure of air in the air box 40 is exerted through the pipe 84 upon the underside of the float 88, tending to raise it and to rotate the lever 93 in a counter clockwise direction as shown in Figure 1. This movement is resisted by the spring 95 which is contained within the adjusting cylinder 96. This spring is compressed between a pin 97 anchored on the bracket 98 on the box 85 and between the cap or cover 99, of the cylinder 96. The other end of the cylinder is covered by a 70 cap 100 associated with a turn buckle 101 pivoted in one of the holes 102 on the lever 93. The tension of the spring may be adjusted by manipulating the turn buckle. Fine adjustment is obtained by means of the weight 103 adapted

to slide along the yoke 104 on the lever 93 and provided with a set screw 105 to lock the weight in place.

Referring now to Figure 2, it will be noted that immediately beneath and at the end of the deck or platform which forms the upper boundary of the marble pack is a fixed chute 106, which terminates at a pivoted gate 107. The gate comes up against a stop plate 108 and this gate is mounted for rotation with the shaft 109. The shaft 109 comes out through the wall 15 and carries a lever 110. This lever is provided at one end with an adjustable counterweight 111, at the other end it has a series of holes in one of which is pivoted a yoke 112 connected by means of a turn buckle 113 with one of the adjusting holes 114 on the lever 93 so that upward movement of the float 88 in response to increased pressure in the air box will tend to open the gate 108 and allow an increased discharge of heavy material down through the chute 115.

Overlying the chute 106 is a middlings chute 116, pivoted at 117 on the plate or wall 15 and 25 adapted to be raised or lowered by manipulation of the handle 118 associated with the quadrant 119 and the locking screw 120 so as to raise and lower the receiving edge of the middling chute and control the maximum depth of the refuse bed. This chute 116 discharges over a fixed chute 121, which terminates in turn at the gate 122 which gate is mounted on the pivot shaft 123, which carries a lever 124 with its adjustable counterweight 125 and is connected at the other 30 end by means of the turn buckle and linkage 126 with the lever 93. The adjustability of the pivot points of the connections between the levers 110 and 124 and the lever 93 gives a wide range of response of gate opening to the variation 35 in pressure of air in the air box. The numeral 127 indicates a coal chute pivoted at 127a and provided with an adjusting quadrant 128 whereby it may be raised and lowered and locked in position by means of the adjusting screw 129 so as to control the depth of the middlings zone.

It will be noted that in the devices of Figures 2 and 7, the adjustment of the coal chute and the middling chute is independent of the position of the plates 71 and 72 or the grid iron 63. 40 In the device of Figure 9, however, the plates 76 and 77 are attached to the chutes, 76 being attached to a slightly different form of coal chute 130, and the plate 77 to a slightly different form of middling chute 131 so that in this case the adjustments of the height of the plate 45 and of the chutes themselves must be made synchronously.

It will be noted that while the refuse chute and the middling chute are shown in the drawings as not being full of material, nevertheless they will normally be filled and the control of the flow clear back to the separating zone will be responsive to the variation of the pressure in the air box. If too much middlings and refuse back up, that will tend to increase the resistance to air flow and the pressure in the air box will increase and so the gates will open to permit more escape of refuse and middlings and thus the operation will be maintained substantially constant. Attention is also called to the fact that the marble pack in Figure 6 decreases more rapidly in thickness from the receiving to the discharge end than it does in Figure 2. This variation in thickness depends altogether upon the conditions of operation, the rate of

flow, the character of the coal or material to be treated, its size, etc. The middlings passing through the gate 122 will be discharged through a chute 132, the refuse passing over the coal chute 126 will be discharged through a chute 133.

The pivot 53 Fig. 5 will be held in its slot 58 by a filler block 134, held in place by a set screw 135 after the parts have been assembled so as to make sure that the response to the adjusting means at the receiving end of the air pack will be a proper and controlled one. In Figure 4 is shown the detail of the marble pack. For instance, the lower plate 47 is slotted, the upper plate 46 is perforate. These plates may be of any suitable shape, they may be stamped or they might be built up of wire cloth as the case may be depending altogether upon the circumstances.

It will be understood that substantially all the apparatus except the air box and marble pack is the same no matter what material is being treated. If, for instance, we have a device such as is shown in Figure 2 and we want to treat a different kind of material, finer or coarser as the case may be or different in other characteristics, we would first remove as a unit that part of the apparatus on the left hand side of Figure 2 and Figure 1 containing the chutes and gates. To do this we would merely disconnect the two turn buckles 113 and 126 from the lever 93 and the chutes, gates and associated parts could be removed as a unit. Then the air box would be lowered until it was supported on the rollers, the locking screws 60 being meanwhile released. Then the air box with its marble pack would be slid forwardly out of the apparatus, first disconnecting the two flexible conduits leading one to the air compressor, the other to the float chamber. Then a different air box and marble pack would be put in place, the chute head would be returned, the marble pack would be adjusted and locked in place and operation could be resumed.

Experience shows that the marble pack is the most satisfactory means for controlling the air flow. It can be easily adjusted. It is simple, does not wear out and gives a nice control of the air resistance. But under some circumstances a fabric may be used in place of the marbles. In this case a series of fabric layers which may be of wire screen or cloth or any suitable material as indicated in Fig. 11 at 138 would be used.

I claim:

1. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, a plurality of chutes having horizontal cutting edges opposed to the flow of material, means for manually adjusting the height of each chute with respect to the discharge end of the floor, gates associated with said chutes remote from the floor, and means automatically responsive to variations in the pressure beneath the resistance bed for controlling the position of said gates.

2. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, a plurality of chutes having horizontal cutting edges

opposed to the flow of material, means for manually adjusting the height of each chute with respect to the discharge end of the floor, gates associated with said chutes remote from the floor, means automatically responsive to variations in the pressure beneath the resistance bed for controlling the position of said gates, and manual means for adjusting the response of said gates to the automatic control means.

3. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, a plurality of chutes having horizontal cutting edges opposed to the flow of material, gates associated with said chutes remote from the floor, and means automatically responsive to variations in the pressure beneath the resistance bed for controlling the position of said gates.

4. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, a plurality of chutes having horizontal cutting edges opposed to the flow of material, gates associated with said chutes remote from the floor, means automatically responsive to variations in the pressure beneath the resistance bed for controlling the position of said gates, and manual means for adjusting the response of said gates to the automatic control means.

5. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, a plate having a relatively large number of apertures substantially larger than the size of the material particles being treated suspended in the stream of material above and generally parallel with the floor.

6. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, a plate having a relatively large number of apertures substantially larger than the size of the material particles being treated suspended in the stream of material above and generally parallel with the floor, and means for imparting to said plate a reciprocatory movement in general parallelism with the plane thereof.

7. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, and an open work structure suspended in the stream of material above the floor generally parallel to the floor and adapted to partially support the weight of material in the stream.

8. A material classifying device comprising a pervious fixed inclined floor, means for feeding a

relatively deep stream of material to be classified downwardly therealong, a resistance bed beneath the floor, means for discharging a pulsating current of air upwardly through the resistance bed and the stream of material, an open work structure suspended in the stream of material above the floor generally parallel to the floor and adapted to partially support the weight of material in the stream, and means for imparting to such structure a reciprocation in general parallelism with the floor.

9. A material classifying device comprising a pervious fixed inclined floor, means for feeding a relatively deep stream of material to be classified downwardly therealong, a resistance bed beneath the floor, means for discharging a pulsating current of air upwardly through the resistance bed and the stream of material, an open work structure suspended in the stream of material above the floor generally parallel to the floor and adapted to partially support the weight of material in the stream, means for imparting to such structure a reciprocation in general parallelism with the floor, a reciprocating feeder adapted to supply material to the floor to form the stream, and drive means for the feeder and the open work structure adapted to impart motion to them in general consonance with the rate of pulsation of the air current.

10. A material classifying device comprising a housing open at the bottom, means at one end for supplying material to be classified thereto, means at the other end for withdrawing classified material therefrom, and a closure for the open bottom of the housing comprising an air box and an air pervious high resistance bed integral therewith, the box and bed being removable from the housing, the bed being immediately adjacent the stream of material as it passes through the housing.

11. A material classifying device comprising a housing open at the bottom, means at one end for supplying material to be classified thereto, means at the other end for withdrawing classified material therefrom, a closure for the open bottom of the housing comprising an air box and an air pervious high resistance bed integral therewith, the box and bed being removable from the housing, and means for supplying a pulsating current of air under pressure to the box whereby the air passes upwardly through the resistance bed and through a stream of material traveling therealong, the bed being immediately adjacent the stream of material as it passes through the housing.

12. A material classifying device comprising a housing open at the bottom, means at one end for supplying material to be classified thereto, means at the other end for withdrawing classified material therefrom, a closure for the open bottom of the housing comprising an air box and an air pervious high resistance bed integral therewith, the box and bed being removable from the housing, means for supplying a pulsating current of air under pressure to the box whereby the air passes upwardly through the resistance bed and through a stream of material traveling therealong, the bed being downwardly inclined from the feed to the discharge end of the housing, and means for adjusting the angle of inclination of the bed, the bed being immediately adjacent the stream of material as it passes through the housing.

13. In a material classifying device, a main

frame, a housing carried thereby, a feeder and pulsating air supplying means permanently mounted on the main frame, means removably associated with the housing for receiving and distributing the treated material, an air box having integral therewith an air resistance bed, an air pervious floor removably mounted on the frame and adapted to close one side of the housing, a pneumatic control means for the distributing and receiving devices permanently mounted on the housing, and a flexible removable connection between the air supply means and the air box and between the air box and pneumatic control means.

14. A material classifying device comprising a main frame, a housing mounted thereon, rollers carried thereby, a combined air box and material supporting deck adapted to be removably positioned beneath the housing to close the open bottom thereof, means for causing the air box to travel along said rollers into register with the housing comprising a windlass, a sheave, a cable extending from the windlass over the sheave and anchored on the air box, and a detachable pivot support for the lower end of the air box, the windlass, sheave and cable apparatus being adapted to raise and lower the opposed end of the air box to adjust the angularity of the material supporting deck.

15. A material classifying device comprising a main frame, a housing mounted thereon, rollers carried thereby, a combined air box and material supporting deck adapted to be removably positioned beneath the housing to close the open bottom thereof, means for causing the air box to travel along said rollers into register with the housing comprising a windlass, a sheave, a cable extending from the windlass over the sheave and anchored on the air box, a detachable pivot support for the lower end of the air box, the windlass, sheave and cable apparatus being adapted to raise and lower the opposed end of the air box to adjust the angularity of the material supporting deck, and means for locking the air box in adjusted position in the housing.

16. A material classifying device comprising a housing, open at the bottom, means at one end for supplying material to be classified thereto and at the other end for withdrawing classified material therefrom, a removable air box closing the bottom of the housing, there being integral with the air box a pervious floor upon which the material is supported and along which it travels and a high resistance air pervious pack beneath the floor and between it and the remainder of the box, and means for supplying a pulsating current of air under pressure to the box.

17. A material classifying device comprising a housing, open at the bottom, means at one end for supplying material to be classified thereto and at the other end for withdrawing classified material therefrom, a removable air box closing the bottom of the housing, there being integral with the air box a pervious floor upon which the material is supported and along which it travels and a high resistance air pervious pack beneath the floor and between it and the remainder of the box, means for supplying a pulsating current of air under pressure to the box, the floor being downwardly inclined from the supply end thereof, and means for adjusting the inclination of the floor.

18. A material classifying device comprising a housing, open at the bottom, means at one end

for supplying material to be classified thereto and at the other end for withdrawing classified material therefrom, a removable air box closing the bottom of the housing, there being integral with the air box a pervious floor upon which the material is supported and along which it travels and a high resistance air pervious pack beneath the floor and between it and the remainder of the box, and means for supplying a pulsating current of air under pressure to the box, the floor being downwardly inclined from the supply end thereof, means for adjusting the inclination of the floor, and rollers upon which the box rests when the inclination has been reduced to a minimum whereby the box may be longitudinally withdrawn from the housing.

19. A material classifying device comprising a housing, open at the bottom, means at one end for supplying material to be classified thereto and at the other end for withdrawing classified material therefrom, a removable air box closing the bottom of the housing, there being integral with the air box a pervious floor upon which the material is supported and along which it travels and a high resistance air pervious pack beneath the floor and between it and the remainder of the box, means for supplying a pulsating current of air under pressure to the box, the floor being downwardly inclined from the supply end thereof, means for adjusting the inclination of the floor, rollers upon which the box rests when the inclination has been reduced to a minimum whereby the box may be longitudinally withdrawn from the housing, and adjusting means comprising a windlass, a pulley on the housing, and a cable passing from the windlass over the pulley to the box and anchored thereupon, the means for withdrawing the classified material from the housing being in part in line with the box and adapted to be removed to permit removal of the box.

20. Means for classifying material according to weight, comprising an air box, means for supplying air under pressure in a pulsating stream thereto, a high resistance air pervious bed associated with the box, means for supplying a stream of material to be separated to and causing it to travel along the upper surface of said bed, means immersed within the stream for guiding such material along lines parallel with the surface of the bed, and means at the discharge end of the stream for separating such stream into a plurality of separate streams, one superposed above the other and containing materials of generally homogeneous but different specific gravities.

21. Means for classifying material according to weight, comprising an air box, means for supplying air under pressure in a pulsating stream thereto, a high resistance air pervious bed associated with the box, means for supplying a stream of material to be separated to and causing it to travel along the upper surface of said bed, means immersed within the stream for guiding such material along lines parallel with the surface of the bed, means at the discharge end of the stream for separating such stream into a plurality of separate streams, one superposed above the other and containing materials of generally homogeneous but different specific gravities, and automatic means responsive to variations in the pressure in the box controlling the rate of flow of each stream separately.

22. In a materials separating machine, a main supporting housing, means permanently associated therewith for supplying material to be

treated to the housing, for supplying fluid under pressure to the housing and for imparting to such fluid a pulsating action, an air box having a resistance bed adapted to be removably and adjustably mounted in the housing with the bed in such position that materials to be separated are discharged upon and travel along said bed, means removably associated with the housing and the air box for horizontally dividing the stream of material into a plurality of layers and automatic means responsive to variation in pressure in the air box for controlling the rate of flow of at least one of said streams.

23. A material classifying device comprising a pervious floor, means for feeding a relatively deep stream of material to be classified therewith, means for discharging a current of air upwardly through the floor and the stream of material, and means embedded in the stream of material generally parallel with the floor for preventing localized air blasts through the bed of material, said means comprising a thin plate generally parallel with the floor having a relatively large number of apertures therethrough substantially larger than the maximum size of the particles being treated and means for giving this plate a controlled movement whereby the material as it travels is gently stirred.

24. In an air separator for removing impurities from coal, an inclined trough, a resistance bed forming the bottom of said trough, an air chamber beneath said bed, means for delivering crude coal to the upper end of said trough, means for delivering air to said chamber under pressure, whereby currents of air are forced up through said bed to cause the coal and refuse mixed therewith to flow down said trough, the coal and refuse gradually separating into different strata due to the difference in their specific gravities, a plurality of chutes arranged to receive material from different strata, respectively, at the lower end of said trough, gates for partly blocking said chutes below the bottom of said trough whereby the chutes are maintained full of material, and means responsive to an increase in the air pressure in said chamber due to excess accumulation of material in the trough for increasing the opening of said gates.

25. In an air separator for removing impurities from coal, an inclined trough, a resistance bed forming the bottom of said trough, an air chamber beneath said bed, means for delivering crude coal to the upper end of said trough, means for delivering air to said chamber under pressure, whereby currents of air are forced up through said bed to cause the coal and refuse mixed therewith to flow down said trough, the coal and refuse gradually separating into different strata due to the difference in their specific gravities, a plurality of chutes arranged to receive material from different strata, gates for controlling the flow of material down said chutes, a common mechanism responsive to variations of air pressure in said chamber for controlling said gates simultaneously, and means for adjusting each gate independent of the other.

26. In an air separator for removing impurities from coal, an inclined trough, a resistance bed forming the bottom of said trough, an air chamber beneath said bed, means for delivering crude coal to the upper end of said trough, means for delivering air to said chamber under pressure, whereby currents of air are forced up through said bed to cause the coal and refuse mixed therewith to flow down said trough, the coal and

refuse gradually separating into different strata due to the difference in their specific gravities, a chute for receiving the lower strata consisting of refuse, a chute for receiving the next strata above consisting of mixed coal and refuse, gates in the chutes for maintaining them full and overflowing at all times to thereby maintain the requisite depth of material in the trough at the lower end, and means responsive to variations of air pressure in said chamber for controlling said gates.

27. In an air separator for removing impurities from coal, an inclined trough, a resistance bed forming the bottom of said trough, an air chamber beneath said bed, means for delivering crude coal to the upper end of said trough, means for

5 delivering air to said chamber under pressure, whereby currents of air are forced up through said bed to cause the coal and refuse mixed therewith to flow down said trough, the coal and refuse gradually separating into different strata due to the difference in their specific gravities, a perforated member suspended in the said trough substantially parallel to the bottom thereof and at approximately the upper level of the refuse strata, the openings in said member being large enough to readily pass the largest pieces of coal and refuse, and means for imparting a reciprocating motion to said member to stir the material and facilitate stratification thereof.

EARL STUMP.
